(57) **CLAIM**

The ornamental design for a display screen with graphical user interface, as shown and described.

DESCRIPTION

FIG. 1 is a front view of a display screen with graphical user interface;

FIG. 2 shows the design of FIG. 1, shown in the context of a new environment;

FIG. 3 is a second embodiment thereof; and,

FIG. 4 is a third embodiment thereof.

The broken line showings in each of the drawing Figures of the display screen with graphical user interface illustrate environmental structure and form no part of the claimed design.

The broken line immediately adjacent to the outer edge perimeter of the graphical user interface shows a display screen and forms no part of the claimed design.
